UNITED STATES PATENT OFFICE.

FRED FORREST PEASE, OF EAST BRAINTREE, MASSACHUSETTS.

LAUNCHING APPARATUS.

Application filed June 17, 1920. Serial No. 389,599.

To all whom it may concern:

Be it known that I, FRED FORREST PEASE, a citizen of the United States, residing at East Braintree, in the county of Norfolk and State of Massachusetts, have invented certain new and useful Improvements in Launching Apparatus; and I do hereby declare the following to be a full, clear, and exact description of the invention, such as will enable others skilled in the art to which it appertains to make and use the same.

The present invention relates to launching apparatus and more particularly to apparatus of this character designed to launch a lifeboat or similar craft from a vessel or land station.

The desirability of a launching device which will insure the launching of a lifeboat well clear of the ship no matter how heavy or rough the sea and without danger of entanglement with the launching gear will be self-evident to those skilled in the art. Launching gears at present in use are difficult to handle in a rough sea and are not capable of successfully launching a boat clear of the vessel.

It is one object of the present invention to provide a comparatively simple and efficient launching apparatus which shall insure that a boat will be invariably launched upon an even keel and at a considerable distance from the vessel.

It is a further object of the invention to provide a launching device which is relatively inconspicuous and occupies a small space when supporting the boat in the inboard position.

It is a still further object of the invention to provide a launching apparatus which may be controlled in its entirety by a single operator without liability of the lifeboat becoming entangled with the launching gear.

With these and other objects in view, the various features of the invention consist in certain novel features of construction, combinations and arrangements of parts herein-after described and claimed, the advantages of which will be obvious to those skilled in the art from the following description.

In the accompanying drawings, Fig. 1 illustrates partially diagrammatically a side elevation of the launching device supporting a lifeboat in the inboard position with the device in outboard position ready to launch

a boat, shown in dotted lines; Fig. 2 is a detail illustrating a top plan view of the launching device swung partly outward from the inboard position; Fig. 3 is a detail of a portion of the tackle employed to control the movement of the launching device; and Fig. 4 is a view looking fore and aft along the vessel and showing the launching device in outboard position at approximately the point at which the lifeboat becomes water borne.

The present invention comprises essentially a boat supporting member together with means for moving the member simultaneously outwardly, downwardly and lengthwise of the launching platform. The boat supporting member is mounted upon the upper ends of a plurality of arms hinged at their lower ends to the side of the vessel or other support in such a manner that the arms move outwardly, downwardly and lengthwise of the launching platform to deposit the lifeboat well clear of the platform. The boat supporting member may be either a cradle or a member of some form from which the boat is suspended by tackle which may be readily disengaged when the boat reaches the water. In the preferred form of the invention a cradle is employed which supports the boat from underneath and this cradle is hinged to the upper ends of the supporting arm in such a manner that it

will be constantly maintained in an upright position with respect to the launching platform during the outward and downward movement of the supporting arms. This construction is simple and particularly efficient as it launches the boat well clear of the vessel and avoids any liability of the boat becoming entangled in launching tackle. As soon as the cradle reaches the water the boat becomes water borne and immediately leaves the cradle which continues its downward movement toward the side of the vessel. In

connection with the launching apparatus, means are provided for constraining the movements of the cradle with respect to the vessel so that it may not swing freely with relation thereto during the movement from inboard to outboard position. Furthermore, after the boat is launched from the supporting cradle and the latter continues its downward movement toward the vessel any subsequent rolling or pitching of the vessel tends

ing to move the cradle upwardly toward the water will bring the cradle to the surface of the water between the lifeboat and the vessel, avoiding any liability of the cradle 5 engaging with and injuring the boat.

In the illustrated embodiment of the invention a cradle 10 consisting of three cradle members 12 rigidly connected by a longitudinal member 14 is supported upon a plurality of parallel arms 16. These arms, in the present case three in number, are hinged at 17 upon the side of the vessel or launching platform above the water line and at 18 to the underside of the cradle. The two sets of hinges for the upper and lower ends of the arms are arranged parallel to the deck of the vessel or the surface of the launching platform but the axes of the several hinges which are parallel to one another are inclined with respect to these surfaces. The result of this construction is, as shown in the drawings, that as the arms 16 swing outwardly to move the cradle from inboard to outboard position the cradle is moved outwardly, downwardly and longitudinally of the vessel while constantly retained in an upright position. Each of the arms 16 is connected adjacent the upper hinge 18 with a guy cable 20 which extends from this point of connection with the arm to a fixed point 22 on the vessel or launching platform. In the illustrated embodiment of the invention the connection points 22 preferably consist of ring bolts 23 set into the deck of the vessel and it will be observed that these points 22 are spaced inwardly from the side of the vessel upon which the hinges 17 are located. The points of connection 22 of the cable 20 in each case are coincident with the axis of the corresponding hinge 17 so that in effect each arm 16 with its cooperating cable 20 forms a triangular supporting member hinged upon a line extending through the hinge 17 and connection 22. It will be observed from an inspection of Fig. 2 that each of the hinges 17, in addition to being angularly disposed with respect to a horizontal plane passing through the vessel, is also inclined with respect to a vertical plane, the upper end of each hinge being tipped inwardly to cause the axis of the hinge pintle to pass through the cooperating connection 22.

It is important in any form of launching apparatus that the launching of a boat may be accomplished by a single operator without danger or liability of the launching gear becoming entangled during the launching of the boat. The present form of launching apparatus is particularly well adapted for this purpose, as will be evident from the following description. The launching cradle which supports the life-boat is connected upon its underside with what may be termed a paying out line 30

which is wound about a drum 31. This line, as shown in Fig. 2 of the drawings, may be conveniently connected with the cradle through a bridle 33 the opposite ends of which are secured to distance pieces 32 fastened to the underside of the cradle. In addition, the side of the cradle and one of the supporting arms 16 is connected with a second line 35 wound about a drum 36 and designed to be taken in as the cradle moves from inboard to outboard position. As will be obvious from an inspection of Fig. 3, the line 35 passes through a sheave 37 connected with the side of the cradle and thence extends to a ring bolt 38 secured to the arm 16 at a point below the upper hinge 18. The two runs of the line where it passes through the sheave 37 are enclosed by a ring 40, the arrangement being such that when the line is wound upon the drum the tendency is to pull the sheave 37 toward the connection point 38 and move the cradle bodily outwards. It will be observed from an inspection of Fig. 2 that the line 35 passes from the ring 40 directly to a sheave 42 secured to the vessel either at or beyond the foremost connection 22 and from this point rearwardly, to the drum, around a pulley block 43. With this construction by properly designing the diameters of the two drums 31 and 36 they may be mounted upon the same shaft and the line 30 payed out as the line 35 is taken in so that the cradle is held between the two lines in such a manner that it cannot swing free with respect to the vessel or launching platform. The drums 31 and 36 are mounted upon the same shaft and may be conveniently operated through gearing 45 by a motor 46 controlled in any suitable manner.

The advantage of such a system of control for the launching apparatus must be self-evident to those skilled in the art as the pull upon the line 35 is sufficient to initiate the outward movement of the cradle even although the launching device as a whole may be encased with ice or otherwise prevented from freely moving, whereas when the cradle is well clear of the vessel this line which is constantly fore-shortened as the cradle moves to outboard position prevents any backward movement of the cradle with respect to the vessel which would otherwise be liable to occur when launching in a heavy sea. The advantages furthermore of having a system of one man control are particularly evident, as in the present construction this control may be removed at some distance from the launching point and the operator stationed within a deck house or other shelter where his control will be unimpeded.

In the usual operation of the apparatus, more especially in a rough sea where the vessel may be rolling or pitching, the life-

- boat is filled with the required number of passengers and the motor then started to move the cradle with the boat carried therein sufficiently to just clear the vessel or into 5 the position shown approximately in Fig. 2. When the vessel then starts to roll toward the side on which the launching device is positioned, the motor is immediately started to move the cradle into an outboard 10 position and when the cradle has been moved a sufficient distance outward the current is thrown off and the motor allowed to run free, the launching cradle and supporting arms then dropping, due to their 15 own weight, until the cradle reaches the water level when the boat immediately becomes water borne and is lifted off the cradle in the direction of the length of the vessel while the cradle continues its falling 20 movement through the water. Should the roll of the vessel cause the cradle to be brought to the surface suddenly it will pass upwardly between the boat and vessel without danger of injuring the boat. After the 25 boat is launched clear of the cradle the motor is operated in the reverse direction to bring the cradle back to inboard position. In connection with the freeing of the lifeboat from the cradle, it will be noted 30 upon referring to Fig. 3 that the cradle is provided with a wedge-shaped socket 44 for the reception of the keel of the lifeboat which is so designed that while the weight of the lifeboat is supported by the cradle 35 the former will not slide longitudinally even though the cradle may be tipped to some considerable degree, but immediately when the lifeboat reaches the water level, it will become water borne and be readily freed from the sockets 44.
- The present invention also contemplates means for handling a plurality of lifeboats with one and the same launching apparatus and to this end, as shown in Figs. 1 and 45 2, an overhead track 50 is provided from which one or more lifeboats may depend through sliding connections, indicated at 51. When the first boat has been launched from the cradle, the latter is returned to 50 inboard position, as shown in dotted lines in Fig. 2, and the second boat moved along the track 50 into position above the cradle at which time it is disconnected from the track and supported by the cradle. This 55 process may then be repeated until the desired number of boats have been launched. It will be observed from an inspection of Fig. 2 that in the inboard position, the cradle with the lifeboat supported therein 60 is conveniently located in a recess 53 formed in the deck at the side of the ship and so located with respect to the hinges 17 that the three arms 16 when in this position are inclined inwardly from the vertical, thus 65 tending to hold the cradle in this position and permitting it to be lashed rigidly in place. In order to permit this nesting of the boat and cradle in the recess, the side of the vessel between the hinges 17 and the cradle is conveniently recessed sufficiently to 70 receive the arm 16 when the launching device is supported in inboard position.
- It will be evident to those skilled in the art that although the present launching device has been shown and described as particularly adapted to the launching of life-boats from vessels, it is also well adapted 75 for the launching of boats from stationary places, as land stations or lighthouses and may in addition be employed for the launching of hydroplanes from vessels.
- It is to be understood that the term "launching platform" as employed throughout the specification and claims is for convenience of description and embraces any 80 type of platform whether forming a part of the vessel or stationary member, such as a wharf, landing stage or lighthouse.
- While it is preferred to employ the specific construction and arrangement of parts 85 shown and described, it will be understood that this construction and arrangement is not essential except so far as specified in the claims, and may be changed or modified without departing from the broader features 90 of the invention.
- The invention having been described, what is claimed is:
1. A launching apparatus comprising a cradle, a plurality of diagonal arms hinged 100 at their lower ends to a launching platform and at their upper ends to the cradle with the axes of the hinges inclined to the cradle and parallel to one another to move the cradle from inboard to outboard position 105 in a path which extends outwardly, downwardly and lengthwise of the launching platform.
  2. A launching apparatus comprising a cradle, a plurality of supports for the cradle hinged upon parallel axes inclined to the launching platform, and a plurality of 110 hinges connecting the supports with the cradle turning about axes parallel to the first mentioned hinges.
  3. A launching apparatus comprising a cradle, a plurality of diagonal arms supporting the cradle, a pair of diagonal hinges connecting the top and bottom of each arm with the cradle and launching platform 115 respectively, the axes of all of the hinges being inclined with respect to the launching platform and parallel to one another.
  4. A launching apparatus comprising a plurality of diagonal supporting arms 120 hinged at their bottom ends to the launching platform, a cradle and hinge connections between the top ends of the arms and the cradle designed to invariably maintain the cradle in the same angular relation with re- 125

spect to the launching platform as the arms swing to move the cradle from inboard to outboard position.

5. A launching apparatus comprising a plurality of diagonal arms hinged to the launching platform at their lower ends, a plurality of guys connecting the upper ends of the arms, each guy being connected at its opposite end to the launching platform at a point coincident with the axis of the hinge connection in the lower end of the arm.

6. A launching apparatus comprising a cradle, means for supporting the cradle constructed and operating to move the latter from inboard to outboard position in a path extending outwardly and downwardly, two

lines connected with the cradle, and means for paying out one line and simultaneously drawing in upon the second line.

7. A launching apparatus comprising a cradle, a plurality of supporting arms hinged at their upper ends to the cradle and at their lower ends to the side of the vessel, guys connecting the upper ends of the arms with fixed points upon the vessel coincident with the axes of the lower arm hinges, two sets of line connected with the cradle, and means for simultaneously paying out one line and drawing in upon the second line to move the cradle from inboard to outboard position or vice versa.

FRED FORREST PEASE.
